(57) **CLAIM**

The ornamental design for an adherence container, as shown and described.

DESCRIPTION

FIG. 1 is a front prospective view of a first embodiment of an adherence container according to the present design;

FIG. 2 is a front side view of the adherence container of FIG. 1;

FIG. 3 is a back side view of the adherence container of FIG. 1;

FIG. 4 is a right side view of the adherence container of FIG. 1;

FIG. 5 is a left side view of the adherence container of FIG. 1;

FIG. 6 is a top view of the adherence container of FIG. 1; FIG. 7 is a bottom view of the adherence container of FIG. 1;

FIG. 8 is a front prospective view of a second embodiment of an adherence container according to the present design; FIG. 9 is a front side view of the adherence container of FIG. 8;

FIG. 10 is a back side view of the adherence container of FIG. 8;

FIG. 11 is a right side view of the adherence container of FIG. 8;

FIG. 12 is a left side view of the adherence container of FIG. 8;

FIG. 13 is a top view of the adherence container of FIG. 8; FIG. 14 is a bottom view of the adherence container of FIG. 8;

FIG. 15 is a front prospective view of a third embodiment of an adherence container according to the present design; FIG. 16 is a front side view of the adherence container of FIG. 15;

FIG. 17 is a back side view of the adherence container of FIG. 15;

FIG. 18 is a right side view of the adherence container of FIG. 15;

FIG. 19 is a left side view of the adherence container of FIG. 15;

FIG. 20 is a top view of the adherence container of FIG. 15; and,

FIG. 21 is a bottom view of the adherence container of FIG. 15.

The broken lines in the drawings are directed to unclaimed portions of the adherence container. Accordingly, the broken lines form no part of the claimed design.

1 Claim, 21 Drawing Sheets
